(57) **CLAIM**

The ornamental design for a mouthpiece for an inhalation device, as shown and described.

DESCRIPTION

FIG. 1 is a perspective view of a mouthpiece for an inhalation device. The broken lines are for illustrative purposes only and form no part of the claimed design;

FIG. 2 is a side view thereof;

FIG. 3 is a front view thereof;

FIG. 4 is a top view thereof; and,

FIG. 5 is a bottom view thereof.
